COTTON SETTING MACHINE

Robert Fox, Chelsea, Mass.

Application September 26, 1936, Serial No. 102,661

3 Claims. (Cl. 93—36)

My present invention relates to paper box making machines, and more particularly to a machine which aligns and fixes the cotton padding to the top of the cover of fancy paper boxes. 5 Many fancy paper boxes used for candy and various other products are provided with a padded top which gives the appearance of a cushion between the heavy cardboard of the top and the outside printed, embossed, or otherwise 10 treated covering.

In the past, it has been the practice to employ skilled labor for the purpose of affixing this padding to the top of the cover. The process is referred to in the trade under the expression of 15 "cotton setting", the padding is composed of cotton fiber being enclosed on each side by thin sheets of paper the whole of which is cut to exact size the over all dimensions of which are smaller than the outside edges of the cover and the 20 padding sheet must be accurately centered within the borders of the top of the cover such that an equal distance is present at all points around the edges. This is essential because after the 25 padding is fixed with glue to the top the combined top and padding attached is then passed through a machine which applies the finished covering to the box top. Heretofore, girls skilled in placing this cotton padding have been used but at its best it is a slow operation due to the 30 accuracy necessary and the fact that it has been mostly a matter of accuracy of the eye.

Having the above facts in mind I have designed a machine which not only locates and attaches this cotton padding but at the same time 35 makes it absolutely unnecessary to use skilled labor. With this device one unskilled operator is able to turn out as much production as several skilled operators previously could produce in the same time. Also each piece turned out is absolutely accurate and perfect.

The principal object of my invention is an improved cotton setting machine;

Another object is an improved machine for setting cotton padding on the top of fancy paper 45 boxes;

Still another object is a cotton setting machine which aligns up the cotton padding and attaches the same to the paper box cover automatically;

50 And still another object is an improved machine of the class above described which provides a yielding contact and automatically provides a graduating adjustment, and

Other objects and novel features comprising 55 the construction and operation of my machine

will appear as the description of the same progresses.

In the drawings illustrating the preferred embodiment of my invention,

Fig. 1 is a side elevation of the machine, the 5 intermittent clutch drive being not shown as it comprises no part of my present invention;

Fig. 2 is a plan view of the machine;

Fig. 3 is an enlarged cross-section of the machine taken on the line 3—3 of Fig. 1; 10

Fig. 4 is a perspective view of one of the gauge members which guide the cotton padding which rests on the feed platform;

Fig. 5 is a bottom plan of a box cover to which a cotton pad has been attached, and 15

Fig. 6 is a side elevation of the box cover shown in Fig. 5 showing the completed operation on the cover before the final finish paper or other material is applied.

Referring more in detail to the drawings, 10 20 indicates a table which may be constructed of any desired material and of any convenient design, wood being used in my present machine. To the table 10 are bolted supporting angle members 11. These angle members are preferably 25 arranged over either slots in the table 10 or provided with slots in their base legs such that they may be moved in or out to vary the size of the setting of the gauges depending on the size of box cover being processed. In the present invention, I have indicated by the numeral 12 slots 30 in the table 10 bolts 13 being shown to clamp the said angle members in place. To the tops of the angle members 11 on all four sides I have affixed horizontal slotted adjustment slide-way 35 members 14 and 15. At the center position of these members 14 and 14 I have fixed vertical guides 14a and 14a, the member 14a on the far side of the machine in Fig. 1 being indicated in Fig. 3. These members 14a may be permanently 40 fixed to the horizontal slide-way members 14. The angle members 11 at ninety degrees to the side angle members are solidly fixed to the end horizontal slide-way members 15. Slidably mounted on the horizontal slide-way members 15 45 are similar guide members 15a which are provided with attached horizontal slide pieces 16, better shown in Fig. 4. Duplicate sets of guides 15a are likewise mounted on the opposite end slide-way and also on each end of the side slide- 50 ways 14. These guides 15a are also provided with screws 17 and wing-nuts 18 so that they may be moved to any desired position and fastened there. On the tops of the guide members 14a I have attached angle brackets 19 to which are 55

attached on opposite sides of the machine flat strips 20, and on top of the strips 20 are gauge angles 21. In a similar manner I have attached angle gauge brackets 22 to angle brackets 23 which in turn are secured to the tops of the gauge members 15a.

Under the center of the table 10 I have positioned a plunger shaft 24 which is provided with a key 25 which is slidably engaged through bearing members 26 secured to the table 10. The top of the shaft 24 is secured to a vertically movable feed platform 27 by means of a threaded housing 28 or by any other suitable means. The lower end of the shaft 24 is reduced in diameter at 29 and is guided through a brace member 30 which is secured to the under side of the table 10. Between the bottom shoulder of the shaft 24 and the brace member 30 I have provided a compression spring 31 bearing against washers 32. On the lowermost end of the reduced shaft 29 I have pivoted a link 33 which is provided with an internal slot 34 through which is pivoted a pin 35. The pin 35 is located in the side of a disc 36 at a point near its periphery. The disc 35 is centered on a shaft 36a which is connected up to an intermittent drive and clutch of conventional design, not shown, so that one movement of the disc comprises a complete revolution, the position shown in Fig. 1 being the start and stop position.

In operation, the platform 27 is normally in a low position, as shown in Fig. 1. In this position, the platform is loaded with a stack of sheets of cotton padding, as indicated broadly at 37. In this position the pin 35 holds the link 33 in a lowered position which in turn compresses the spring 31. The operator now picks up a box cover which comprises the cardboard top 38 with the sides 39 attached and draws the outside top surface of this cover across a glue roll which deposits a small amount of glue on this outer surface. The cover is now placed up-side-down on the machine, the long sides of the edges of the cover resting on the strips 20 against the gauges 21 and the ends of the cover resting against the gauges 22. The operator now starts the machine, either by foot or hand, and at the same time holds one hand on the upper side of the box cover as it rests on the machine. The disc 36 makes one revolution which allows the shaft 24 to rise with the platform 27 until the top sheet of cotton padding contacts the glued under side of the box cover on the machine. At this point, if the platform 27 is provided with a number of cotton padding members the link 33 will not rise as far as when the platform is empty, the spring 31 will be slightly compressed at this point owing to the pressure of the operator's hand on the cover being treated. When the platform recedes as the pin 35 picks up the link 33, the operator removes the box cover which now has the cotton padding sheet 37 attached and repeats the process with another cover.

Having thus described my invention what I claim as new is:

1. An improved machine for attaching cotton padding to the covers of paper boxes comprising

in combination, a base member comprising a table top upon which the said paper box covers are handled, horizontal gauge slide-ways mounted on said table top, said gauge slide-ways being adjustable, the side and end slide-way members being adjustable toward each other with the end and side slide-way members moving on said table top at ninety-degrees to each other, vertical guide members horizontally slideable and adjustably mounted on said slide-ways and means for securing the end vertical members in temporary positions for the accommodation of different size box covers, a feed platform located within the confines of said vertical gauges and adapted to move up and down carrying a plurality of sheets of cotton padding, a shaft located below said platform and attached thereto and guided in said table top and a brace member located below said table top, a compression spring located on said shaft below said table top and above said brace member and normally adapted to maintain said platform in an elevated position, a slotted link pivoted to said shaft and having a pivot pin engaging in said slot and being adapted to slide up and down in said slot, a disc connecting with said pin being adapted to rotate and permit said link to rise and fall as the said compression spring elevates said platform and said pin depresses said platform, shaft and link.

2. An improved machine for attaching cotton padding to the covers of paper boxes comprising in combination, an operating base comprising a work table from which said machine is operated, horizontally adjustable slideways mounted on said base, said slide-ways being adjustable in a horizontal direction at ninety-degree angles, vertical guide members horizontally adjustable in said slide-ways, a vertically movable platform mounted inside said vertical guide members, an elevating shaft attached to the under side of said platform, a compression spring surrounding said shaft at its uppermost portion, a guide brace member in which the lower portion of said shaft is slidably mounted, said brace being below the lower end of said spring, a link pivotally connected to the lower end of said shaft and having an internal vertical slot therein, a crank pin engaged in said slot, a fly-wheel connected to said pin being adapted to permit said link to rise and further adapted to draw down said link when said pin is in its lowermost position.

3. An improved machine for attaching padding to the covers of paper boxes comprising, in combination, a frame, padding gauges for positioning sheets of padding, cover gauges for engaging the edges of box covers and positioning said covers with respect to the positioned padding sheets, said padding and cover gauges all being adjustably supported from the frame in normally fixed position with respect thereto, a feed table adapted to carry a plurality of superposed padding sheets, a plunger attached to said feed table adapted to operate said feed table for the purpose of contacting said padding with a positioned cover, and means for intermittently operating said plunger, substantially as shown and described.

ROBERT FOX.
